UNITED STATES PATENT OFFICE.

THOMAS PERCY BUTLER, OF NEW YORK, N. Y.

ROTARY ENGINE.

SPECIFICATION forming part of Letters Patent No. 712,119, dated October 28, 1902.

Application filed December 9, 1901. Serial No. 85,204. (No model.)

To all whom it may concern:

Be it known that I, THOMAS PERCY BUTLER, of the borough of Manhattan, city, county, and State of New York, have invented 5 a new and useful Improvement in Rotary Engines, of which the following is a specification.

I will describe a rotary engine embodying my improvement and then point out the novel 10 features in the claims.

In the accompanying drawings, Figure 1 is partly a central longitudinal section and partly an elevation of an engine embodying my improvement. Fig. 2 is a transverse section of the same, taken at the dotted line 2 2, Fig. 1. Fig. 3 is a transverse section of certain parts of the same, taken at the dotted line 3 3, Fig. 1. Fig. 4 is a transverse section of certain parts, taken at the line 4 4, Fig. 1. 20 Fig. 5 is a transverse section of one of the parts, taken at the line 5 5, Fig. 1.

Similar letters of reference designate corresponding parts in all the figures.

$A' A^2 A^3$ designate the casing of the engine. 25 As here shown, it is of cylindric form, and that will doubtless be the most desirable. The body A' is provided at its edges with flanges, which may be secured by bolts to the heads $A^2 A^3$. Inside the cylinder are secondary 30 heads $A^4 A^5$, and these are located at considerable distance inward of the heads $A^2 A^3$, so that chambers $B' B^2$ will be formed between the heads of each pair. The main heads $A^2 A^3$ are provided with inwardly-extending rims a . Between these rims and the body A' of the casing are annular spaces. 35 The secondary heads $A^4 A^5$ abut against the inner ends of the rims a . The secondary heads $A^4 A^5$ have central openings, and projecting outwardly from these openings and 40 preferably through the heads $A^2 A^3$ of the casing are cylinders a' . All the parts which I have described are stationary.

The piston C of the engine is affixed to a 45 shaft C' , journaled in the cylinders a' , the latter being made to constitute bearings, which may be packed in any desired manner.

The piston C has a body c' , preferably made of cylindric form. A number of rib-coils c^2 50 extend spirally around this body and, as here

shown, continuously from end to end. Between these rib-coils are a number of partitions or abutments c^3 . Preferably these abutments, which extend between the different rib-coils c^2 , will coincide. They are represented as so doing, and hence as forming other rib-coils c^3 , which intersect the spiral ribs c^2 . The rib-coils c^2 and the abutments c^3 are either formed integral with or fastened to the cylindric body c' of the piston. In the abutments 60 c^3 are openings c^4 .

The numbers and proportions of the various parts may be modified according to the judgment of the constructor to meet different conditions and to adapt the engine to different purposes. 65

A cylindric shell c^5 forms part of the piston and is secured to its rib-coils. It extends into the space between the rims a of the heads $A^2 A^3$ and body A' of the casing. 70

Steam-pipes $D' D^2 D^3$ supply steam to the chambers $B' B^2$. The pipe D' may communicate with either of the pipes $D^2 D^3$ under control of a valve D^4 . Steam, therefore, may be introduced into either of the chambers $B' 75 B^2$ for the purpose of causing rotation of the piston C in either direction. Openings $b' b^2$, formed in the secondary heads $A^4 A^5$, provide for the entrance of steam into the spaces between the rib-coils c^2 . Steam is exhausted 80 from these spaces through either of two pipes $E^2 E^3$, which extend through the secondary heads $A^4 A^5$ and communicate with a pipe E' under control of a valve E^4 . As shown, the valves $D^4 E^4$ are provided with handles, which 85 are connected by a rod F , so that both valves may be operated in unison.

When steam is admitted through the pipe D^2 , it is exhausted through the pipe E^3 , and when admitted through the pipe D^3 it is exhausted through the pipe E^2 . 90

The steam passes through the openings c^4 in the abutments c^3 , and intermediate of adjacent abutments it acts upon the rib-coils c^2 .

As shown, the openings c^4 in the abutments 95 are at an angle to the faces of the abutments. The openings $b' b^2$ in the secondary heads $A^4 A^5$ are also shown as being at an angle to the faces of these heads. The oblique disposition of the openings c^4 gives them a tend- 100

ency to direct the steam against the rib-coils c^2 , and the oblique disposition of the openings $b' b^2$ gives the latter a tendency to direct steam against the faces of the abutments c^3 .

While this engine is specially adapted for steam, it is not intended to restrict its use to that particular motive agent.

What I claim as new, and desire to secure 10 by Letters Patent, is—

1. The combination with an internally-circular casing, of a rotary piston comprising a body or shaft, rib-coils extending spirally around said body or shaft, and abutments 15 extending across the space between adjacent rib-coils and outwardly from said body or shaft, said abutments being constructed to provide openings.

2. The combination with an internally-circular casing, of a rotary piston comprising a body or shaft, rib-coils extending spirally around said body or shaft, and abutments extending across the space between adjacent rib-coils and outwardly from said body or 25 shaft, said abutments being provided with openings extending outwardly from the body or shaft.

3. The combination with an internally-circular casing, of a rotary piston comprising 30 a body or shaft, rib-coils extending spirally around said body or shaft, and abutments extending across the space between adjacent rib-coils and outwardly from said body or shaft, said abutments being provided with 35 openings having oblique sides.

4. The combination with an internally-circular casing, of a rotary piston comprising a body or shaft, rib-coils extending spirally around said body or shaft, and other rib-coils 40 extending in the reverse direction around said

body or shaft, openings being provided through one of the sets of rib-coils.

5. The combination with an internally-circular casing, of a rotary piston comprising a body or shaft, rib-coils extending spirally 45 around said body or shaft, abutments extending across the space between adjacent ribs and outwardly from said body or shaft and constructed to provide openings, and an outer shell, all said parts being connected together 50 to be rotated in unison.

6. The combination with an internally-circular casing, two main heads and two secondary heads for said casing, constructed to form induction and eduction chambers for the 55 motive agent, of a rotary piston comprising a body or shaft, rib-coils extending spirally around said body or shaft, and abutments extending across the space between adjacent rib-coils and outwardly from said body or 60 shaft and constructed to provide openings.

7. The combination with an internally-circular casing, two main heads and two secondary heads provided with oblique openings for said casing, and constructed with said 65 main heads and casing to form induction and eduction chambers for the motive agent, of a rotary piston comprising a body or shaft, rib-coils extending spirally around said body or shaft, and abutments extending across the 70 space between adjacent rib-coils and outwardly from said body or shaft and constructed to provide openings.

In testimony whereof I have signed my name to this specification in the presence of 75 two subscribing witnesses.

THOMAS PERCY BUTLER.
